209,441

COMBINED ELECTRIC CAN OPENER AND ICE CRUSHER

Donald L. McFarland, Long Beach, and Daniel E. McCue,
Huntington Beach, Calif., assignor to Rival Manufacturing Company, a corporation of Missouri

Filed Nov. 28, 1966, Ser. No. 4,823

Term of patent 14 years

(Cl. D95—2)

Fig. 1.

Fig. 2.

Fig. 3.

Fig. 4.

Fig. 5.

FIG. 1 is a front elevational view of a combined electric can opener and ice crusher showing our new design;
 FIG. 2 is a rear elevational view thereof;

FIG. 3 is a side elevational view thereof, taken from the left-hand side of FIG. 1;

FIG. 4 is a top plan view thereof; and

FIG. 5 is a side elevational view thereof, taken from the right-hand side of FIG. 1.

We claim:

The ornamental design for a combined electric can opener and ice crusher, as shown.
